UNITED STATES PATENT OFFICE.

HENRY F. HEUMANN, OF PERCY, ILLINOIS, ASSIGNOR OF ONE-HALF TO GEORGE A. LICKISS, OF PERCY, ILLINOIS.

SAFETY POWDER-CAN.

1,248,491.

Specification of Letters Patent.

Patented Dec. 4, 1917.

Application filed June 16, 1915. Serial No. 34,457.

To all whom it may concern:

Be it known that I, HENRY F. HEUMANN, citizen of the United States, residing at Percy, in the county of Randolph and State 5 of Illinois, have invented a new and useful Safety Powder-Can, of which the following is a specification.

This invention relates to an improvement in safety powder cans, and the object is to 10 provide means for discharging the powder from a can or receptacle into cartridges without danger of spilling the powder or over-filling the cartridge.

The invention is intended more particularly for use by coal miners, and the object 15 is to provide a can which may be conveniently used for the purpose of filling cartridges without danger of explosion.

A further object is in the provision of a 20 valve for controlling the discharge of the powder from the receptacle. This valve is preferably made of copper for the purpose of eliminating friction which might produce a spark and cause an explosion of the 25 powder.

The invention consists of certain novel 30 features of construction and combinations of parts, which will be hereinafter described and pointed out in the claims. It is evident that many slight changes may be made in the 35 form and arrangement of the several parts to be described, without departing from the spirit and scope of the invention, and hence I do not wish to be limited to the exact construction herein set forth.

In the accompanying drawings,

Figure 1 is a perspective view of a can embodying the invention.

Fig. 2 is a longitudinal vertical sectional 40 view.

Fig. 3 is a horizontal sectional view on the line 3—3 of Fig. 2.

Fig. 4 is an enlarged detail sectional view on the line 4—4 of Fig. 2.

Fig. 5 is a fragmentary view in top plan 45 of the cover.

Fig. 6 is a perspective view of the valve.

A represents the receptacle or can, which is provided with an opening 1 in the side 50 wall thereof. Extending from the wall of the can, and around the opening, are a plurality of plates, an upper plate 2, bottom plate 3 and side plates 4, all of which are substantially triangular in form, and taper 55 outwardly from the receptacle A. The edges

of the upper plate 2 are connected to the upper edges of the side plates 4, and the edges of the bottom plate 3 are connected to the lower edges of the side plates 4, so as to form a pyramidal hopper-like structure, 60 constituting the discharge of the can A.

Connected to the outer ends of the plates 2, 3 and 4, is a spout 5, through which the powder is discharged from the hopper. Connected to the upper end of the upper plate 65 2, and at the juncture between the upper end of the plate 2 and the wall A, is a curved or concaved strip 6. The terminals of the strip 6 are connected to the sides 4. Connected to the lower edge of the metal strip 6 is a 70 downwardly inclined plate 7, the ends of the plate being connected to the sides 4. Slidably mounted against the inner face of the upper plate 2, and above the strip 6 and the inner plate 7, is a valve or slide 8. The 75 lower terminal of the valve is directed obliquely into the inner end of the spout 5, owing to the inclined position of the upper wall or plate 2 of the hopper, for the purpose of closing the spout to prevent the discharge of powder from the can A. An elongated slot 9 is formed in the upper plate 2. A knob 10 is provided with a stem 11, which passes through the elongated slot 9 of the upper plate 2 and through the valve 85 8. A nut 12 is screwed upon the inner end of the stem and binds against the lower face of the valve 8 for fastening the same to the stem. The valve is reciprocated by sliding the knob 10 against the outer side of the 90 hopper for opening and closing the spout 5. The valve 8 passes through an opening formed between the terminals of the upper plate and the inner plate.

The valve 8 is preferably made of copper 95 for the purpose of eliminating any friction which might produce a spark and ignite the powder thereby causing an explosion.

A handle 13 is connected to the wall of the can or receptacle A, diametrically opposite the spout 5, so that the can or receptacle may be tilted, or lifted and held at the desired angle to insert the spout into the cartridge for the purpose of filling it without danger of spilling the powder.

A cover consisting of sections 14 and 15 is mounted on the receptacle for forming a closure therefor, the section 14 of the cover being rigidly held to the receptacle or can A, and the section 15 is hinged to the sec- 110

tion 14. The outer or free end of the hinged section 15 of the cover is adapted to be supported on lugs 16, formed on the inner wall of the receptacle or can A below 5 the upper edge of the can.

A projection 17 is formed on the upper edge of the can or receptacle, and projects inwardly. A slot or notch 18 is formed in the edge of the cover section 15, through 10 which the projection 17 passes as the cover section is moved to its closed position and upon the lugs 16.

A pivoted latch 19 is connected to the section 15, and one edge of the latch is adapted to be inserted beneath the projection 17 15 for fastening the cover section 15 in closed position.

Ears 20 are connected to the wall of the can or receptacle A, and connected to the 20 ears is a bail 21 for use in carrying the receptacle or can from one destination to another.

From the foregoing it will be seen that I have provided a can or receptacle in which 25 powder can be placed for the purpose of filling cartridges, and the like, without danger of overfilling the shells or spilling the powder. The valve 8 is in a position to be easily and quickly operated so that the discharge of the powder from the receptacle 30 may be easily controlled.

The bail 21 admits of the easy carrying of the can in upright position, and as the hopper and spout project laterally from the can, 35 the can may be easily set down upon a flat surface, will be maintained from tilting over by its flat bottom, and may be easily lifted for transportation. The provision of the rigid handle 13 on the opposite side of the 40 can to that from which the hopper and nozzle project, admits of the quick lifting and tilting of the can, and the ready application of the spout to the cartridge.

The general practice employed by miners 45 in filling shells or cartridges is to pour the powder directly from the original container into the cartridges or shells. This is very unsatisfactory because there is danger of spilling the powder and overfilling the 50 cartridges. With the present invention the powder can be transferred from the powder keg or container to the can or receptacle A by raising the cover section 15, and after the can or receptacle has been filled the cover 55 can be lowered and held in closed position by the latch 19, and the receptacle will then be ready for filling cartridges, shells and the like.

The strip 6 and the inclined plate 7 form 60 a guard on the inside of the hopper. This guard is spaced inwardly from the top wall of the hopper and completely incloses the valve 8 to keep the powder away from the valve. By the use of this guard, the valve 8 65 may be shifted back and forth to open and

close it without frictional contact with the powder, and without danger of igniting the same.

It will also be noted that the valve 8 is 70 slidably mounted against the top wall of the hopper, which top wall is inclined outwardly and downwardly. This mounting of the valve directs its lower closing end into a downwardly and forwardly inclined position in the inner end of the spout 5 when 75 the valve 8 is closed, so that the valve constitutes practically a continuation of the top wall of the hopper.

When the can A is full of powder, the latter 80 fills the hopper and presses against the valve 8. As the valve is opened the powder gravitates through the hopper and outwardly 85 through the spout 5 beneath the valve 8. This pouring of the powder outwardly through the spout 5 without tilting the can 85 is permitted by the pyramidal shape of the hopper which substantially merges into the top, the bottom and the sides of the can, and the inclined position of the valve.

What is claimed is,—

1. A safety powder can having a supporting bottom and an open side, four plates projecting outwardly from the marginal edges of said open side and each being of substantially triangular form, the plates being secured together along their meeting edges and converging to a point substantially midway between the top and bottom of the can, the top and bottom plates leading from points adjacent the top and bottom 100 of the can and the side plates converging from the opposite rounded sides of the can and constituting substantially continuations of the same, a spout connected at its inner end to the converging outer ends of the 105 plates, said plates and spout completing a pyramidal hopper which closes the open side of the can and is in communication with the interior of the latter, said hopper extending from the transverse center of the can nearly 110 to the top and bottom thereof, and a valve slidably mounted upon the top plate and thereby set in an inclined position and extending into the spout to close communication with the can, and a guard secured to the 115 side and top plates and extending across and in spaced relation from and in rear of the valve and the top plate to form a top wall for the hopper and keep the powder away from the valve.

2. A safety powder can having a supporting bottom and an open side, four plates projecting outwardly from the marginal edges of said open side and each being of substantially triangular form, the plates being secured together along their meeting edges and converging to a point substantially midway between the top and bottom of the can, the top and bottom plates leading from points adjacent the top and bot- 130

tom of the can and the side plates converging from the opposite rounded sides of the can and constituting substantially continuations of the same, a spout connected at its inner end to the converging outer ends of the plates, said plates and spout completing a pyramidal hopper which closes the open side of the can and is in communication with the interior of the latter, 10 said hopper extending from the transverse center of the can nearly to the top and bottom thereof, and a valve slidably mounted upon the top plate and thereby set in an inclined position and extending into the spout 15 to close communication with the can, a curved strip connecting the side plates in rear of the top plate, and an inclined plate secured between the side plates in rear of the

top plate and extending forwardly and downwardly from the lower edge of the 20 curved strip to which it is secured, said strip and said inclined plate providing a guard spaced from the top plate of the hopper to house the valve, and prevent contact of the powder therewith, and to direct the powder 25 downwardly into the spout, whereby when the valve is open the powder may gravitate from the upper end of the can into the spout.

In testimony that I claim the foregoing as 30 my own, I have hereto affixed my signature in the presence of two witnesses.

HENRY F. HEUMANN.
